W. A. ENDTER
CARTON VENDING DEVICE
Filed Feb. 18, 1926

INVENTOR.

WALDEMAR A. ENDTER.

BY.

W. A. Endter
ATTORNEY.

UNITED STATES PATENT OFFICE.

WALDEMAR A. ENDTER, OF LONG BEACH, CALIFORNIA.

CARTON-VENDING DEVICE.

Application filed February 18, 1926. Serial No. 89,036.

This invention relates to a device for vending paper cartons in which semi liquid or solid food, such as oysters, ice-cream, salad and the like are sold.

5 An object of my invention is to provide a device of the character stated, from which the cartons may be readily taken one at a time and with very little effort.

10 Another object is to provide a sanitary and sightly container for paper cartons.

Other objects are simplicity of construction and effectiveness in operation.

15 Other objects, advantages and features of invention may appear from the accompanying drawing, the subjoined detailed description and the appended claims.

In the drawing illustrating my invention.

Fig. 1, is a front elevation of my vending device.

20 Fig. 2, is a sectional view taken on line 2—2 Fig. 1.

Fig. 3, is a fragmentary sectional view taken on line 3—3 Fig. 2.

25 Fig. 4, is an enlarged fragmentary sectional view showing the carton retaining roller and support therefor.

Fig. 5, is a fragmentary front view of a device showing a slightly modified form of carton retainer.

30 Fig. 6, is an enlarged sectional view taken on line 6—6 Fig. 5.

Referring more particularly to the drawing, my vending device comprises a substantially rectangular cabinet 1, on the front

35 of which a door 2 is provided. The door extends from a wall 3 across the front of the cabinet to adjacent the bottom of said cabinet, a space 4 being left at the bottom through which the cartons are withdrawn.

40 The cartons 5 are nested in each other, and the bails 6 thereof extend forwardly and are spaced from the body of the carton as shown in Figs. 2 and 4. The bails are formed of metal having sufficient stiffness

45 to support a column of cartons, and the cabinet is so formed that the cartons will readily fit therein, and still move readily as will be further described.

50 A supporting strip 7, preferably formed of metal is threaded through all of the bails

6, and extends substantially the length of the cabinet. The lower end of the strip extends below the lower edge of the door 2, and the upper end of said strip is supported on a spring clip 8 which extends through a slot therein. The clip rests against a strap 9 secured to the wall 3, and a handle 10 is secured to the end of the clip which protrudes through the wall so that said clip can be retracted to release the strip 7. A pair of rollers 11, are journaled on the lower end of the strip 7, and are preferably formed of a soft fibrous material. The bail 6 of the lower carton 5 rests on the rollers 11 as shown in Figs. 2 and 4 thus supporting the column of cartons in the cabinet. The rollers 11 are spaced apart so that the thumb of the operator can pass between said rollers and press upon the bail. Pressure on the bail 6 causes the rollers 11 to rotate slightly and releases said bail after which a slight downward pull will release the carton, and the next carton above will drop down and rest by its bail on the rollers. Thus a single carton is vended by using only one hand, and without tearing or mutilating them.

In Figs. 5 and 6 I have shown a slightly modified form of vending device in which cartons having no bails are placed. A strip 12 is fastened in the cabinet 1 at the lower end of the door 2, and a notch 13 is provided therein, in which the flaps 14 of the carton 15 is exposed. A pair of spring fingers 16 are secured to the strip 12 and are formed with a small hook 17 thereon, on which the flaps 14 rest. The carton is vended by pushing the flap 14 rearwardly off the hooks 17 and pulling downwardly to release the carton, whereupon the next carton above drops down upon the hooks.

If desired a glass panel 18 can be set in the door 2, so that the number of cartons in the cabinet can be ascertained.

Having described my invention I claim.

1. A device for vending cartons comprising a cabinet having an opening adjacent the lower end thereof, said cabinet being adapted to contain a column of nested cartons having bails thereon, a strip in said cabinet, rollers on said strip, said rollers

engaging the bails as the cartons are vended through said opening.

2. A device for vending cartons comprising a cabinet having an opening adjacent the lower end thereof, said cabinet being adapted to contain a column of nested cartons having bails therein, a strip removably mounted in said cabinet, said strip being

adapted to be threaded through the bails, a pair of spaced rollers journaled on the lower end of said strip, said rollers being adapted to engage the bail of the lower carton to support said cartons in the cabinet.

In testimony whereof I affix my signature.

WALDEMAR A. ENDTER.
